(57) **CLAIM**

The ornamental design for a display device, as shown and described.

DESCRIPTION

The present application is related to U.S. Design patent application Ser. No. 29/663,749, filed concurrently herewith, the entire disclosure of which is incorporated herein by reference.

FIG. 1 is a perspective view of a display device showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is an enlarged view of the area '8' as seen in FIG. 3; and,

FIG. 9 is an enlarged view of the area '9' as seen in FIG. 4. In the drawings, the evenly dashed broken lines illustrate portions of the display device that form no part of the claimed design; all unshaded portions including the unshaded regions immediately adjacent solid lines in FIGS. 1, 2, and 6, form no part thereof. The dash-dot broken lines showing enlarged detail views in FIGS. 3, 4, 8, and 9 are for annotative purposes and form no part thereof.
